C. D. RICHARD

AUTOMATIC TELEPHONE SWITCH

Filed Sept. 7, 1922

Patented June 16, 1925.

1,542,414

UNITED STATES PATENT OFFICE.

CHARLES D. RICHARD, OF WEST NEW BRIGHTON, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed September 7, 1922. Serial No. 586,617.

To all whom it may concern:

Be it known that I, CHARLES DONAT RICHARD, a citizen of the Republic of France, residing at West New Brighton, in the county of Richmond and State of New York, have invented certain new and useful Improvements in Automatic Telephone Switches, of which the following is a full, clear, concise, and exact description.

10 This invention relates to automatic switching apparatus and more particularly to coordinate switches of the type adapted for establishing connections in an automatic telephone system.

15 This invention is particularly adaptable to a switching system of the type disclosed in the patent to Charles L. Goodrum and John N. Reynolds, No. 1,515,735 issued Nov. 18, 1924, but it will be apparent to those skilled in the art that the invention may be applied equally well to perform other switching functions.

20 The object of this invention is to provide a switching mechanism in which the operating parts are made interchangeable and so constructed that they may be readily removed or assembled on the switch frame without necessitating any subsequent adjustment.

25 A feature of the invention resides more particularly in the provision of individual supporting members for each set of passive wire conductors. Guides are provided in said support for guiding the camming cards whereby the active contacts are moved into engagement with their associated passive contacts in a positive manner and whereby each card may be readily moved from its guide independently of the other cards.

30 It is thought that the invention will be best understood from the following detailed description, reference being had to the accompanying drawings in which Fig. 1 is a partial assembly view of said switch showing a selective bar in operated position. Fig. 2 is a top view thereof. Fig. 3 is a side view of Fig. 1, showing the upper set of active conductors in contacting engagement with a set of passive conductors.

35 The structure shown consists in general of a plurality of banks of conductors which comprise the sets of wires 1, 2, 3, 4 and 5, 6, 7, 8, referred to hereinafter as passive conductors, together with vertical rows of

sets of active wire conductors 9, 10, 11, 12 and 13, 14, 15, 16, etc., and operating mechanism for selectively moving the various sets of active contact wires into engagement with their associated passive conductors.

40 The structure may be of any desired width and height to accommodate as many vertical rows of active contact sets and as many sets per row as may be required.

The active contact wires 9, 10, 11, 12 and 13, 14, 15, 16 are arranged in vertical bars of insulation material 17 which are held securely in the portion of the switch frame (not shown) by any suitable means.

45 Each set of active contact wires is provided with an operating card 18 of insulating material, having apertures 19, 20, 21 and 22 through which the active wires extend in juxtaposition to the passive conductors. The operating cards 18 are slidably arranged in guides in the shape of slots 23 cut at suitable intervals into the two laterally extending edges of each bank 36 and held in normal non-operated position therein by means of resilient supports 24 which, like the active contact wires, are embedded in the vertical bar 17. Each resilient support 24 extends through the bank into the lower aperture in the card 18 and is tensioned downwardly so as to normally hold the active contact wires out of engagement with their associated passive conductors. Each card 18 is provided at its upper portion with two laterally extending lugs 25 and 25' which are adapted to limit the downward movement of the card and active contact wires associated therewith.

50 Each bank comprises a plurality of channel members 36 with slots 23 for the cards. Each channel member carries at intervals insulating strips 37 and 38 between which the passive conductors are clamped. The strips 37 and 38 are suitably held to the channel member 36 as by screws 40. This makes it possible not only to replace one set of passive conductors without disturbing another set, but also any wire in the set may be removed without disturbing the other wires.

55 With each vertical row of active contact sets there is associated a vertical rotatable bar 26 which is provided at one end with an armature 27 arranged to be attracted by an electromagnet 28, whereby the bar 26 is

rotated out of its normal position in response to each energization of said electromagnet. On each vertical bar 26 there is provided a number of relatively short arms 29 each associated with a cam 30.

With each set of passive conductors 1, 2, 3, 4 and 5, 6, 7, 8, etc., there is associated a horizontal rotatable bar 31, each of which is provided with an armature 32 and an electromagnet 33, whereby the bar is rotated from normal to off-normal position. Each horizontal bar is provided with a number of cams 30 for operating the camming cards. Each of said cams is individually associated with a set of active contact wires 9, 10, 11 and 12, and a camming card 18. Normally, the cams 30 are free to move in a vertical path without engaging the cards 18. When the vertical bar 26 is rotated out of its normal position by electromagnet 28, the arms 29 carried thereby are moved into a position wherein they intercept the path of their associated cams 30 as shown at 34 in Fig. 3. The continued movement of bar 31 results in rotating the cam 30 and in lifting the camming card 18 so as to permit the active contact wires 9, 10, 11 and 12 to engage the passive conductors 1, 2, 3, 4, respectively. The operating bar 31, together with the cams 30 thereon, remain in their off-normal position throughout the duration of the connection, but the vertical bar 26 may be immediately restored to normal. The cam 30 in its operated position is moved by bar 31 entirely clear of its associated arm 29 so that any subsequent movement of the arm 29 is ineffective to disturb the connections already established. A spring 35 carried by bar 31 is provided for returning the cam 30 to normal position.

What is claimed is:

1. In a switching mechanism, sets of active contacts, an individually removable support, sets of passive contacts arranged on said individually removable support and disposed coordinate to said active contacts, a camming member for each set of said active contacts, slidably arranged in a plurality of guiding slots in said support, and a cam for operatively engaging said member to effect interengagement between said contacts at their crossing point.

2. In a switching mechanism, sets of active contacts arranged in rows on upright supports, sets of passive contacts arranged on supports coordinate to said upright supports, a plurality of camming members for said active contacts slidably arranged in said second mentioned supports, a cam associated with each set of said contacts, and means for selectively operating said cams to effect interengagement between a set of active and passive contacts.

3. In a switching mechanism, sets of passive contacts arranged on supports, sets of active contacts associated therewith, a plurality of camming members slidably arranged in said supports one for each set of said active contacts, a plurality of cams for operating said members, a bar for selectively causing said cams to move into operable relation with said members to effect interengagement between a set of said active and passive contacts, and resilient means for returning said members from operated to normal position. 65

4. In a switching mechanism, active and passive contact sets, a selective mechanism therefor including an operating bar, a plurality of arms carried by said bar, a cam rotatably arranged on each of said arms, another bar disposed outside of the zone of said contacts and at right angles to the first mentioned bar, a plurality of rigid members carried by the second mentioned bar for operatively engaging said cams, a movement of the second mentioned bar followed by a movement of the first mentioned bar being effective to interengage a set of said active and passive contacts. 70

5. In a switching mechanism, active and passive contact sets, a camming card for each set of said active contacts, an individual supporting member for each set of said passive contacts, means in said supporting member for guiding said card. 75

6. In a switching mechanism, disengaged active and passive contacts, a camming card therefor, a cam, a projection extending therefrom for causing said cam to move into operable relation with said card, another projection extending angularly and in the opposite direction from the first mentioned projection, a resilient member cooperating with the last mentioned projection for returning said cam from operated to normal position. 100

7. A switch comprising sets of stationary wire multiples, individual horizontal supports for said sets of wire multiples, sets of movable contacts therefor arranged on vertical supports, a plurality of operating members slidably arranged in guiding slots on each of said horizontal supports, and means for moving one of said operating members in said guiding slots to establish a connection between intersecting sets of stationary wire multiples and movable contacts. 110

In witness whereof, I hereunto subscribe my name this 1st day of September, A. D. 1922. 115

CHARLES D. RICHARD.
